ELECTRIC WATER-HEATER.

1,323,643.

Specification of Letters Patent.

Patented Dec. 2, 1919.

Application filed November 27, 1918. Serial No. 264,426.

To all whom it may concern:

Be it known that we, HARRY A. MULVANY and HARRY E. KENNEDY, citizens of the United States, residing at Berkeley, in the county of Alameda and State of California, have invented new and useful Improvements in Electric Water-Heaters, of which the following is a specification.

This invention relates to an electric water heater.

One of the objects of the present invention is to provide a simple, substantial and cheaply manufactured electric water heater which is particularly adapted for use in standard house boilers and the like and which is so constructed that it may be installed without changing the pipe connections or altering the boiler in any manner.

Another object of the invention is to provide an electric heater which permits slight expansion and contraction with current changes, thereby producing a self-cleaning action, as all scale and any precipitate which would otherwise accumulate and lower the efficiency of the heater, is cracked off.

Another object of the invention is to provide a novel mounting for the heater and terminal box employed in connection therewith, and also to provide means for preventing leakage between the heater and the terminal box.

Further objects will hereinafter appear.

The invention consists of the parts and the construction, combination and arrangement of parts as hereinafter more fully described and claimed, having reference to the accompanying drawings, in which—

Figure 1 is a side elevation of a water boiler partly broken away, showing the application of the invention.

Fig. 2 is an enlarged central vertical section through the heater and the terminal box.

Fig. 3 is a cross section on line 3—3, Fig. 2.

Referring to the drawings in detail, A indicates a standard form of water boiler and 2, the drain opening through which accumulating mud and scale is generally removed. Adapted to be screwed into the drain opening is a T-fitting 3. This fitting is provided in the present instance as a support for the electric water heater generally indicated at B and also as a support for the terminal box C of the heater. The

heater proper consists of a double-walled tube B, which is split, as shown at 4, to permit expansion and contraction of the tube, due to heat variations, and also to form communication between the interior and the exterior of the tube. Mounted between the double walls of the tube is a plurality of heating elements 5, of suitable construction. These elements are insulated from each other and also from the walls of the tube, to prevent short-circuiting of the individual elements. The upper end of the tube or the double walls of which it is formed, is closed as at 6 to prevent admission of water while the lower end of the tube is open as 7 shown at 7 to permit the terminal ends of the heating elements to pass out of the tube and into the terminal box C, each wire being connected to the respective terminal screws 8, as shown, to permit the formation of the circuits desired. The number of terminal screws employed will depend entirely upon the number of separate elements placed within the tube and it is therefore obvious that as many terminal screws are provided as conditions may demand.

The heater consisting of the tube shown and the elements mounted therein, is secured in the T-fitting 3 by means of a threaded bushing 9, the tube being soldered or otherwise secured to the bushing to prevent leakage between the bushing and the tube and also to secure the tube rigidly in the bushing. For the purpose of preventing leakage down through the center portion 10 of the tube and into the terminal box, we provide a pair of plugs such as shown at 11 and 12. Both plugs are soldered within the tube and thereby form a double seal which positively prevents admission of water to the terminal box C. Leakage, if any, that might escape by the bushing 9 or the plug 11 would merely drop on top of the terminal box and run off as the plug 12 would positively prevent water from leaking by this point as the water once escaping by the plug 11 would not be under pressure and would therefore escape in the path of least resistance offered. The T-fitting is provided with a removable plug which permits any mud or accumulating scale to be flushed out from time to time, free escape of water and mud being possible at all times as water cannot only enter through the upper end of the tube but also through the slot 4. This

- slot is open throughout the entire length of the tube and is not closed before the plug 11 is reached. It can therefore be seen that any mud or scale that accumulates on top 5 of the plug or interior of the T-fitting will be positively flushed out as water under pressure has free admission to all points. A heater constructed as here shown, has proven very efficient in constant service as it presents 10 a large heating surface, due to the fact that the water to be heated comes in contact not only with the exterior but also with the interior surface of the tube. It is also efficient, due to the fact that the split in the tube permits it to contract and expand with 15 temperature variations, thereby producing a self-cleaning action as it positively cracks off scale or other precipitants contained in the water.
- 20 Another feature of the present invention is the simplicity of construction which permits it to be cheaply manufactured and readily installed. In fact, any ordinary plumber can make the installation as it is only necessary to remove the old drain plug 25 and insert the T-fitting containing the heater tube and the terminal box, as shown.
- While the heating tube is here shown as being perfectly circular in cross section, it is 30 obvious that the shape may be varied to suit different installations; similarly, that the number of heating elements and the construction of same may be varied and also that the materials and finish of the other parts employed may be such as the experience 35 and judgment of the manufacturer may dictate.
- Having thus described our invention, what we claim and desire to secure by Letters Patent is—
- 40 1. In an electric water heater, a fitting having an upper end formed to be screwed into the drain opening of a water boiler, a heater extending through the fitting and below the lower end thereof, and a terminal box secured to the lower end of said heater, said heater having its upper end projecting above the upper end of the fitting whereby upon screwing of the latter into the boiler 45 the heater will extend into the boiler interior.
2. In an electric water heater, a substantially T-shaped fitting having its upper end threaded so as to be capable of being screwed 50 into the drain opening of a water boiler, a
- heater extending through the vertical leg of the fitting and above said upper end thereof and into the boiler and also extending below the lower end of the vertical leg of the fitting and a terminal box on said lower end of the fitting, the lateral arm of the T-fitting extending below the boiler and having a removable drain plug. 60
3. An electric water heater comprising a T-pipe fitting adapted to be screwed into the drain opening of a water boiler, a double-walled tubular heater extending through the T-fitting and secured therein, a plurality of heating elements disposed between the double walls of the tube and insulated therefrom, a terminal box secured on the lower end of the tube and spaced below the lower end of the T-fitting, and a sealing plug within the tube adapted to prevent leakage between the T-fitting and the terminal box. 65
4. An electric water heater comprising a T-pipe fitting adapted to be screwed into the drain opening of a water boiler, a double-walled tubular heater extending through the T-fitting and secured therein, a plurality of heating elements disposed between the double walls of the tube and insulated therefrom, a terminal box secured on the lower end of the tube and spaced below the lower end of the T-fitting, a sealing plug 70 within the tube adapted to prevent leakage between the T-fitting and the terminal box and a second sealing plug in the lower end of the tube. 75
5. An electric water heater comprising a T-pipe fitting adapted to be screwed into the drain opening of a water boiler, a double-walled split tube extending through the T-fitting and secured therein, a sealing plug in the lower end of said tube, a second sealing plug mounted below the first named sealing plug, a terminal box secured on the extreme lower end of the tube and a plurality of heating elements disposed between the double walls of the tube and insulated therefrom. 80
- In testimony whereof we have hereunto set our hands in the presence of two subscribing witnesses.
